UNITED STATES PATENT OFFICE.

HENRY A. HANSEN AND ROY W. HANSEN, OF CHICAGO, ILLINOIS.

DESIGN FOR COMBINATION LAMP AND PHONOGRAPH STAND.

Application filed September 22, 1921. Serial No. 502,565. Term of patent 14 years.

To all whom it may concern:

Be it known that we, HENRY A. HANSEN and Roy W. HANSEN, citizens of the United States, residing at Chicago, in the county of Cook and State of Illinois, have invented a new, original, and ornamental Design for Combination Lamp and Phonograph Stand, of which the following is a specification, reference being had to the accompanying drawing, forming a part thereof.

The single figure of the drawing is an elevation showing my combination lamp and phonograph stand.

We claim:

The ornamental design for combination lamp and phonograph stand, as shown.

HENRY A. HANSEN.
ROY W. HANSEN.
